H. A. DOUGLAS

CIRCUIT CONTINUING DEVICE

Filed April 4, 1921

Inventor:
Harry A. Douglas

By L. L. Gragg Atty.

UNITED STATES PATENT OFFICE.

HARRY A. DOUGLAS, OF BRONSON, MICHIGAN.

CIRCUIT-CONTINUING DEVICE.

Application filed April 4, 1921. Serial No. 458,555.

My invention relates to circuit continuing devices of the class employing shells and contact carriers movable in the shells for opening and closing the circuit, and has for 5 one of its objects the provision of an improved construction whereby the handle of the switching mechanism is prevented from becoming disassembled from the contact carrier provided therewith and whereby the 10 handle assembles the carrier and shell.

The invention has for another of its objects the employment of a circuit continuing device of the class described in conjunction with a plug insertable laterally therewith. 15 This plug is so interrelated with the shell as to prevent the circuit opening adjustment of the circuit continuing device when the plug is in position.

In carrying out the first object of my invention the shell is provided with a slot 20 through which the switching handle is passed into the contact carrier that is movable within the shell to adjust the relation of the circuit closing contacts, the handle being provided with a transverse groove receiving an edge portion of the slot in the shell to maintain said handle and the contact carrier into which it is inserted in assembly with each other and with the shell, 25 said slot being formed with an enlargement through which said handle may be passed into the contact carrier that is to receive it.

In carrying out the second object of my invention the shell has an opening in its side through which the current conducting plug is insertable into the same contact carrier that is movable within the shell, the shell serving to hold the plug from movement to prevent switching movement of the 40 contact carrier that receives it.

I will explain my invention more fully by reference to the accompanying drawing in which Fig. 1 is a view in elevation of a circuit continuing device constructed in accordance with the preferred embodiment of the invention; Fig. 2 is a sectional view on line 2—2 of Fig. 1; Fig. 3 is a sectional view on line 3—3 of Fig. 1; Fig. 4 is a view similar to Fig. 3 but showing the lateral plug 45 removed and the movable contact carrier, that is within the shell, in a different position; and Fig. 5 is a perspective view illustrating, in separated relation, the shell, the contact carrier that belongs within and is

movable within the shell to constitute it a 55 switching element, and a handle for assembling this contact carrier with the shell.

Like parts are indicated by similar characters of reference throughout the different figures.

The circuit continuing device illustrated includes a metal shell 1 and an insulating contact carrier 2 therein which is preferably rotatable within the bore of the shell to open and close the circuit. This contact carrier is illustrated as being provided with two conducting rods 3 and 4 which are formed with recesses at their outer ends that receive the conducting wires 5 and 6 which are clamped in place by means of the binding screws 7 and 8. The inner ends of these conducting rods 3 and 4 are formed with longitudinal bores in which the contacts 9 and 10 are disposed, springs 11 and 12 being employed to press these contacts 65 outwardly into engagement with complementary contacts 13 and 14 upon the inner end of the base 15 of an incandescent lamp 16. This incandescent lamp base carries bayonet pins 17 which are receivable within the bayonet channels 18 in the adjacent outer end of the shell 1, the springs 11 and 12 serving to maintain the lamp base in assembly with the shell. It is to be understood 70 that the lamp base may be replaced by other 75 forms of contact carrier without departing 80 from the spirit of my invention.

In order that the circuit of the lamp or other translating device may be opened and closed the contact carrier 2 is moved with respect to the contact carrier 15, the contact carrier 2 being preferably turned in order to bring the contacts 9 and 10 into or out of connection with the contacts 13 and 14, the springs 11 and 12 continuing to function to 85 maintain the contact carrier 15 in place whether these springs press the contacts 9 and 10 against the contacts 13 and 14 or against the insulation of the contact carrier 15 that is adjacent the contacts 13 and 14. The contact carrier 2 is provided with a handle 19 by which the contact carrier 2 may be moved and as this contact carrier is preferably turned the shell is provided with a transverse slot 20 through which the handle passes 90 into the contact carrier 2, the ends of the slot 20 defining the range of movement of the handle and the contact carrier to which 100 105

- it is attached, the circuit being opened when the handle is in one end of the slot and closed when the handle is in the other end of the slot. The contact carrier 2 is formed with an opening 21 that receives the inner end of the handle that is preferably slid into this opening without being in threaded connection with the contact carrier 2, though the invention is not to be thus limited.
- 10 In order to maintain the handle and the contact carrier 2 in assembly with each other and with the shell, the handle is provided with a transverse or annular groove 22 that receives at least one transverse edge portion and preferably both transverse edge portions of the slot 20, the portion of the handle circumscribed by the groove 22 being preferably but slightly narrower than said slot. The inner end of the handle is thus 20 larger than the part that is in the slot 20, this enlarged inner end of the handle engaging the edges of the slot to maintain the handle and contact carrier in assembly. This slot is provided with an enlargement 23 through which the inner end of the handle 19 may be passed into the opening 21 when this opening and the enlargement 23 are in register. The throat 24 between the slot enlargement 23 and the slot 20 is desirably also 30 but slightly wider than the portion of the handle 19 circumscribed by the groove 22. When the handle has been inserted through the opening 23 into the opening 21 this groove 22 is in register with the surrounding portion of the shell 1 so that the handle may be moved through the throat 24 into the transverse slot 20, the springs 11 and 12 serving to prevent the handle from reentering the throat 24 and the slot enlargement 23 as the handle is moved from side to side in opening and closing the circuit.
- 40 The device illustrated is so constructed that it may be also employed to supply current to an inspection lamp or other trans- 45 lating device which is adapted to be electrically coupled with the conductors 3 and 4 by means of a lateral plug 25. This plug is provided with two plugging contacts 26 and 27 which are engageable with contacts 50 28 and 29 that are projected by the springs 11 and 12 into the lateral openings 30 and 31 formed in the conductors 3 and 4 to be positioned to be engageable by the contact elements 26 and 27. When the plug 25 is 55 inserted it snugly fits the opening 32 so that the contact carrier 2 cannot then be turned. When the plug 25 is withdrawn the handle 19 may be manipulated to turn the carrier 2 into opening or closing circuit position.
- 60 While I have herein shown and partic- 65 ularly described the preferred embodiment of my invention I do not wish to be limited to the precise details of construction shown as changes may readily be made without departing from the spirit of my invention, but

having thus described my invention I claim as new and desire to secure by Letters Patent the following:

1. In an electric connector, a shell, a circuit continuing plug movably mounted in the shell, a plug operating handle detachably interfitting with said plug and extending through and movable in a slot in the shell, and means on the handle directly coacting with the shell in both on and off positions of the plug to hold the handle against disengagement from the plug.

2. In an electric connector, a shell, a circuit continuing plug movably mounted in the shell, a plug operating handle detachably interfitting with said plug and extending through and movable in a slot in the shell, and means on the handle engaging the inner side of the shell in both on and off positions of the plug to hold the handle against disengagement from the plug.

3. In an electric connector, a cylindrical shell having means to detachably secure a terminal plug in one end thereof, a circuit continuing plug movably mounted in the shell, a detachable plug operating handle for the circuit continuing plug extending through and shiftable along a slot in the shell to move said plug, means effective to permit free engagement and disengagement of the handle with and from the circuit continuing plug when said handle is disposed in one portion of the slot, means on the handle engaging the shell when the handle is in other portions of the slot to prevent disengagement of the handle from the circuit continuing plug, and means operative when a terminal plug is secured in the shell to hold the circuit continuing plug in a position relative to the shell to dispose the handle in a portion of the slot where it is restrained against disengagement from the circuit continuing plug.

4. In an electric connection, a cylindrical shell having means to detachably secure a terminal plug in one end thereof and provided with a slot formed of a portion extending at an angle to the longitudinal axis of the shell and a second portion extending from the first named portion longitudinally of the shell in the direction of said terminal plug securing means, a circuit continuing plug mounted in the shell for rotatable and longitudinal movements relative to the shell, a detachable plug operating handle for the circuit continuing plug extending through and shiftable along the first portion of the slot to rotate the plug and along the second portion of the slot during longitudinal movement of the plug, means effective to permit free engagement and disengagement of the handle with and from the circuit continuing plug when said handle is disposed in a given position in the second portion of the slot, means on the handle engaging the shell when

the handle is in the first portion of the slot to prevent disengagement of the handle from the circuit continuing plug; and means operative when a terminal plug is secured in the shell to hold the circuit continuing plug in a position to dispose the handle in operative position in said first named portion of the slot.

5. A circuit continuing and switching device including a shell; a contact carrier within the shell and adapted to be turned; in combination with a current conducting plug connectable with a current conductor upon said contact carrier, said shell having an opening in its side through which said plug is insertable into the contact carrier, the shell serving to hold the plug from move-

ment to prevent movement of the contact carrier to circuit opening position.

6. A circuit continuing and switching device including a shell; a contact carrier within the shell and adapted to be moved therein; in combination with a current conducting plug connectable with a current conductor upon said contact carrier, said shell having an opening in its side through which said plug is insertable into the contact carrier, the shell serving to hold the plug from movement to prevent movement of the contact carrier to circuit opening position.

In witness whereof, I hereunto subscribe my name this 30th day of March, A. D. 1921.

HARRY A. DOUGLAS.
